(57) **CLAIM**

The ornamental design for a container cap, as shown and described.

DESCRIPTION

FIG. 1 is a front perspective view of a container cap showing the new design with the cap open;

FIG. 2 is a rear perspective view thereof;

FIG. 3 is a left side elevation view thereof with the cap open, with the right side elevation view being a mirror image;

FIG. 4 is a front perspective view thereof with the cap closed;

FIG. 5 is a front elevation view thereof with the cap closed;

FIG. 6 is a rear elevation view thereof with the cap closed;

FIG. 7 is a top plan view thereof with the cap open;

FIG. 8 is a front perspective view of a second embodiment of a container cap showing the new design with the cap open;

FIG. 9 is a rear perspective view thereof with the cap open;

FIG. 10 is a left side elevation view thereof with the cap open, with the right side elevation view being a mirror image;

FIG. 11 is a front perspective view thereof with the cap closed;

FIG. 12 is a front elevation view thereof with the cap closed;

FIG. 13 is a rear elevation view thereof with the cap closed; and,

FIG. 14 is a top plan view thereof with the cap open.
